UNITED STATES PATENT OFFICE.

HERBERT H. WILLIAMS, OF BROOKLYN, NEW YORK, ASSIGNOR TO THOMAS E. MURRAY,
OF BROOKLYN, NEW YORK.

JOURNAL BOX.

1,413,549.

Specification of Letters Patent. Patented Apr. 18, 1922.

Application filed October 2, 1920. Serial No. 414,282.

To all whom it may concern:

Be it known that I, HERBERT H. WILLIAMS, a citizen of the United States, and resident of Brooklyn, New York, have invented certain new and useful Improvements in Journal Boxes, of which the following is a specification.

My invention aims to provide certain improvements in journal boxes and provides a practical method of manufacturing such boxes or the principal parts thereof of stamped or forged steel; thus permitting a considerable reduction in the weight, a more accurate and a stronger product, and effecting a reduction in the cost of manufacture.

My invention also makes it possible to form the various parts with absolute uniformity and to combine them solidly and accurately into a journal box which is not only lighter but is also of greater strength and more uniform dimensions than have been possible by previous methods.

The accompanying drawings illustrate an embodiment of the invention.

Figs. 1, 2, 3, 4, 5 and 6 are perspective views illustrating respectively the complete box, an inside stop piece, a dust guard casting, an arch bar seat and upper and lower segments of which the cellar is formed;

Figs. 7 and 8 are respectively longitudinal and transverse vertical sections on the correspondingly numbered lines in Figs. 8 and 7;

Figs. 9, 10, 11 and 12 are views similar to Figs. 7 and 8 illustrating modified details.

The principal feature of the invention is the making of the cellar of two segments, illustrated for example, in Figs. 5 and 6, of sheet metal drawn, pressed or stamped into shape and afterwards united along their edges to form the complete cellar ready for the addition of the other parts. The journal box shown is of the Master Car Builders' type and is divided along a horizontal longitudinal plane. The upper segment comprises the top 11 of the cellar and flanges 12 forming parts of the sides thereof which are bent in to form the usual outer grooves 13 for the fastening bolts of the car bolster. The sides 12 at their inner ends are bent outward to form portions 14 of the edges of the dust guard pocket, extending beyond the inner edge of the top 11 and united by a plate 15 which forms part of the inner wall of said pocket. The line of division between the two segments, indicated by dotted lines

in Figs. 7 and 8, is located above the lower edge of the outside opening on which rests the usual lid or cover. The outer end of the upper segment, Fig. 5, is, therefore, open.

The lower segment, Fig. 6, includes the bottom plate 16 of the cellar and side portions 17 with grooves 18 and portions 19 and 20 of the edges and inner wall of the dust guard pocket, these parts registering with the parts 12, 13, 14 and 15 of Fig. 5. These two segments are brought together along their horizontal edges and united by welding. For this purpose we may use, for example, the electric welding method described in the patent of Thomas E. Murray, jr., No. 1,281,636 of October 15, 1918.

The box may be divided along various other lines than those illustrated. For example, it might be divided along a vertical longitudinal plane into two symmetrical halves afterwards welded together. Or it might be divided into more than two segments, to be united along various lines. And the segments might be shaped to include only the cellar proper, without the dust guard pocket, or to include in addition several of the other elements hereinafter referred to and generally shown as separate parts welded in place.

Assuming the segments of Figs. 5 and 6 united as described we have the finished cellar of Fig. 1 with its top wall 11, bottom wall 16 and side walls 21, and with the ends 22 and rear wall 23, Fig. 7, of the dust guard pocket complete.

The arch bar seat 23^a, Figs. 1 and 4, is made of a single rolled steel plate welded on the top of the cellar and with bolt openings aligned with the grooves 24 in the sides of the latter.

The tie bar seat 25 is also made of a separate piece of rolled steel bent up to form flanges 26 embracing the sides of the cellar and is welded to the bottom of the latter and has the necessary bolt openings in line 100 with the grooves 24. The design of the arch bar seat and also of the tie bar seat will depend upon the kind of car and bolster with which the journal box is to be used. The exact dimensions of these parts and particularly the distances between their bearing faces and from such bearing faces to the inside stop pieces of the journal box are of considerable importance, and greater accuracy can be secured by making them of 110

rolled or sheet steel than by making them or either of them of cast steel or iron.

The inside stop piece which supports the axle bearing has also to be dimensioned and proportioned with great accuracy and I secure this result by making a separate inside stop piece, preferably also of sheet metal. Preferably I shape this as in Fig. 2 of a plate 27 welded on the underside of the top of the cellar and provided with downward side flanges 28 and 28' constituting the guides or side stops for the bearing blocks and with a short forward flange or flanges 29' constituting front stops therefor. Preferably also at the rear edge of the plate 27 I bend up a flange 29 constituting part of an outer wall of the dust guard pocket opposite the inside wall 23 thereof. See Fig. 7.

Instead of bending up the flange 29 to form part of the pocket from the end of the inside plate 27, as in Fig. 7, the top 11 of the cellar may be bent up as in Fig. 10 to form a flange 30 serving the same purpose, the plate 27 having its end flush with the face of the flange 30.

The top of the box is usually provided with a door hinge lug cast integrally. I prefer to make such a lug in a separate piece as indicated at 31, Figs. 1 and 7, and to weld the edges thereof on the top 11 of the cellar.

However, this lug may be formed as in Fig. 9, by extending the top 11 of the cellar outward and bending it up in a flange 32 and back on itself in a second flange 33, the edge of which may be welded to the plate.

Or this lug may be formed as in Fig. 11 by extending the central part of the plate 27, the part between the lugs 29', forward and bending it upward in a flange 34 and back on itself in a second flange 35, the edge of which is welded to the top plate 11.

The dust guard pocket with its end walls 22 and its outer and inner walls 29 and 23, carries a separate dust guard casing 36, Figs. 3 and 7, with an outward flange 37 around its upper edge. As illustrated it is made of a single piece of sheet metal stamped with the required flanges and with openings 38 and 39 and then bent up along the edges of the bottom 40 as shown in Fig. 7. It fits in the dust guard pocket, with its flange 37 extending over the top of the latter. When in place it is held with its edges together and there is no necessity of welding such edges, though they may be welded for convenience in handling.

In some types of journal box the bottom of the dust guard pocket and casing are open to permit dust to fall through, and such a design may be adopted in journal boxes made according to this invention.

In order to hold the inside stop piece more firmly against the strains to which it is subjected in the direction of the car axle,

the walls of the cellar may be shaped to fit in the space between the flanges 28' and thus to lock the stop piece against inward or outward movement. Fig. 12 shows such a scheme. The upper part of each side wall 70 of the box is bent inward to form a projection 41 to fill the space between the flanges 28' of the stop piece. This forms on each side of the box a depression in line with but somewhat deeper and wider than the grooves 75 24 which carry the fastening bolts. The stop piece contains all the stops usual in this style of journal box, front and back stops for the wedge and side guides for the wedge and the journal bearing.

By the use of this stop piece it is possible to secure absolutely accurate and uniform dimensions at the points required without the necessity of any other machining. The forming of the dust guard casing of stamped 85 steel secures a uniform and smooth receptacle for the insertion of the dust guard. It is advantageous also to form the arch bar and the tie bar seats separately of stamped or forged steel. They can thus be made 90 accurately and uniformly and can be conveniently fastened to the cellar.

The various parts may be fastened together in numerous ways. The preferred method is by electric welding. Other means 95 may be employed however, such as riveting or a combination of riveting and welding, to accomplish the same result; and welding by other than electrical methods may also be used.

The particular order in which the parts are assembled in the manufacture of the journal box is chiefly a matter of convenience and may be varied according to the method of fastening the parts together. In 100 welding them as described, for example, the stop piece and hinge lug and the pocket casing are preferably assembled with the upper segment of the cellar before this is united to the lower segment; and after such union the arch bar seat 23^a is welded on the upper segment and the tie bar seat 25 on the lower segment. A fin of metal will generally be extruded along the inner and outer faces of the welded joints, and this will be removed, at least in so far as it interferes with the application of the seats 23^a and 25 and with the use of the journal box.

The dividing of the cellar along the horizontal plane calls for a comparatively short line of weld, which makes the drawing of the segments comparatively easy and which also makes it easy to get at and to remove the fins formed in the welding operation. It also locates these fins where they will not interfere with the mounting of the inside stop piece and the top and bottom seats.

The description above refers to one standard type of journal boxes. There are many types of such boxes differing in detail from 130

that illustrated and it is understood that the invention is applicable to practically all such designs of box. For passenger cars, for example, it is usual to provide two outer grooves 5 on each side for the fastening bolts instead of single grooves as shown at 24. Such double grooves can be equally well formed in the segments of the cellar. And the shapes of the parts may be otherwise altered to produce a variety of special designs adapted 10 for different styles of car bolster or pedestal and for different modes of attachment to the box.

Though I have described with great particularity in detail certain embodiments of my invention, yet it is not to be understood therefrom that the invention is restricted to the particular embodiment disclosed. Various modifications thereof in detail and in the 15 arrangement of the parts may be made by those skilled in the art without departing from the invention as defined in the following claims.

What I claim is:

25 1. A journal box the cellar of which consists of a plurality of sheet metal segments meeting each other edge to edge and united by butt-welding along the entire line of their meeting edges and leaving their faces smooth.

30 2. A journal box the cellar of which con-

sists of two sheet metal segments meeting each other along horizontal longitudinal edges at the sides of the cellar and united by butt-welding along the entire line of their meeting edges and leaving their faces smooth. 35

3. A journal box the cellar of which consists of sheet metal segments welded together and forming the top, bottom and sides, in combination with an arch bar seat, a tie bar seat and an inside stop piece, each separately 40 formed and fastened to the cellar.

4. A journal box having a top, a bottom and sides of sheet metal and having a separate arch bar seat thereon.

5. A journal box having a separate inside 45 stop piece on the underside of the top of the cellar said inside stop piece having a flange forming part of the dust guard pocket.

6. A journal box having a cellar of two sheet metal segments welded together and a 50 dust guard pocket having two parts, one of which is integral with each of the respective segments of the cellar.

7. A journal box having a cellar and a dust guard pocket and having a separate dust 55 guard casing in said pocket.

In witness whereof I have hereunto signed my name.

HERBERT H. WILLIAMS.
